C is a geometrical figure representing a portion of a many-pointed star, which is drawn around a central cross, a.

D is a representation of a portion of a wall inclosing a tree, b, with flowers c and leaves trailing and overhanging the wall.

E is a figure resembling an arch, partially filled in with lattice-work d; and F is a figure resembling part of a window-frame, with lattice-work partly filling in the space inclosed by the frame.

A branch, e, embellished with flowers, extends from the figure F, as shown.

A bouquet, B, of flowers is between and connects the figures C, D, and E, a branch of said bouquet reaching nearly to the branch e.

I claim—

5. The design for a carpet, consisting in figures C and D and intervening flowers, substantially as shown.
6. The design for a carpet, consisting in figures D and E and intervening flowers, substantially as shown.
7. The design for a carpet, consisting in figures C and E and intervening flowers, substantially as shown.
8. The design for a carpet, consisting in figures C, D, E, and F and intervening flowers, substantially as shown.

The above description of my invention signed by me this 21st day of October, 1879.
